UNITED STATES PATENT OFFICE.

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE.

TYPEWRITING MACHINE.

Application filed October 16, 1924. Serial No. 743,899.

This invention relates to typewriting machines, and more particularly to paper-feeding and controlling devices therefor, in which a plurality of superposed work-sheets 5 with interleaved carbon-sheets may be gripped and fed between the feed-rolls, and in which the work-sheets may comprise, as a first or top sheet, a relatively narrow statement-sheet, and as a second sheet a 10 wider or ledger-sheet. More particularly, the present invention relates to means for relatively positioning or collating the several work-sheets after these work-sheets have been inserted around the platen, between the platen and the feed-rolls.

The present invention presents improvements over the mechanism disclosed in the patents to H. W. Harris, No. 1,433,718, and No. 1,433,817, both dated October 31, 1922.

20 This invention can be used for a variety of work, as, for example, typing statements and ledger-sheets. The same ledger-sheet is used with a succession of statements. The ledger-sheet may be wider than the statement, and the two sheets may be inserted around the platen of a typewriter with the narrow statement-sheet on the outside, a carbon intervening between the sheets for making duplicate entries upon the ledger- 30 sheet.

The ledger-sheet may contain items previously typed thereon, and at each insertion it is desired to bring this ledger-sheet into proper relation with the printing line 35 of the typewriter, so that the next line of typing will fall beneath the previous items thereon. This is required to be done even though the ledger is covered up by the narrow statement-sheet. The statement- 40 sheet is originally positioned properly when inserted in the machine, so that the first line of typing will fall at the desired point thereon.

45 Previous to placing these sheets in the machine, they are assembled out of proper typing relationship to each other, that is, with the first blank space on the ledger-sheet at a point above the first blank space on the overlying statement-sheet. Said preliminary adjustment of the sheets is not 50 final; the final adjustment of the ledger-sheet being effected after the sheets are inserted in the typewriter.

To effect this final adjustment, the pre-

viously positioned outside or statement-sheet is held stationary by means of clamps engaging the margins thereof, while the inside sheet is fed backwardly, by means of auxiliary feed-rolls engaging with its exposed side margins. Said rolls co-operate 55 with the platen to move the ledger sheet downwardly to collate it with the statement, that is, to bring the first blank line on the ledger-sheet into coincidence with the printing line on the platen. Then the outer sheet may be unclamped and the typing 60 may proceed, line by line, both sheets being fed by the usual bottom feed-rolls. These bottom-feed-rolls are released during 65 the described preparatory adjustment of the sheets; the sheets being collated upon a table erected at the delivery side of the platen.

The statement-sheet is filled up with items which are added from day to day, or at 70 other intervals. When out of the typewriter, it may be clipped to the ledger-sheet or otherwise connected thereto, for convenience in reinserting both in the machine from time to time as required. When 75 a ledger-sheet is filled up, a new one is substituted.

For facilitating the adjustment of the underlying ledger-sheet to the printing line during insertion thereof into the typewriter, 80 a pencil mark in its side margin is made by the operator, at the conclusion of the typing of each entry. This mark guides the operator subsequently in bringing the ledger-sheet down to the same point where the last 85 item was typed; and then the operator advances the sheet one or two line-spaces, preparatory to beginning the typing of the next item.

The collating table is mounted on the 90 platen-frame, and carries paper-clamps to hold the narrow sheet against the table while the wider sheet is moved around by means of the platen, to collate the sheets.

One of the features of this invention relates to means for laterally positioning the work-sheets relatively to the platen, and to each other, previously to their being inserted 100 around the platen. To this end, there are provided a plurality of pairs of gages, adjustably mounted upon a table at the introductory side of the platen, the inner gages being lower than the outer gages,

to permit the wider sheets to lie over the inner gages and still be gaged by the outer gages.

According to another feature of this invention, provision is made to actuate both paper-clamps by the operation of either, and to resiliently hold both clamps in either effective or ineffective position. The clamps are pivotally mounted upon a table at the delivery side of the platen and are operatively connected by means of a reciprocating link effective to swing one of the clamps when the other clamp is operated. The clamps are held in either effective or ineffective position by means of over-center springs operatively connecting the clamps with the supporting table.

Other features and advantages will hereinafter appear.

20 In the accompanying drawings,

Figure 1 is a front view, showing the invention as applied to the platen-frame of a typewriting machine.

Figure 2 is a plan view of the paper-clamps, showing means to co-ordinate their operation.

Figure 3 is a cross-sectional view through line 3-3, looking in the direction of the arrows.

30 Figure 4 is a cross-sectional view through line 4-4, looking in the direction of the arrows, and shows the adjustably-mounted work-sheet guides.

Figure 5 is a detail plan view, showing 35 the co-operative relation between the paper-clamp and the thumb-lever, and the method of mounting the clamp upon the supporting table.

The platen 10, of the usual cylindrical 40 type, is carried by an axle 11, journaled in end frames 12 and 13 and is manually operable by means of a finger-wheel 14.

There are also shown the ordinary feed-rolls 15 and 16, spring-pressed paper-fingers 45 17, each provided with a pressure-roll 18 adjustably mounted upon tie-rod 19, and a paper-chute or paper-table 20.

Mounted upon the end frames 12 and 13 there is a table 21, parallel to the platen 50 10, which has ears 25 formed for the purpose of carrying rock-shafts 23 operatively connecting paper-clamps 22 and thumb-levers 24, said paper-clamps 22 being arranged to co-operate with the table 21 to positively hold a work-sheet 34. The paper-clamps are actuated by an over-center-spring 55 arrangement which permits springs 26 to either hold said clamps 22 against the table 21, as shown in Figure 2, or to hold said clamps 22 in their ineffective position, as shown in said Figure 2 in dot-and-dash lines.

In order that one clamp 22 may be operated by the other and that simultaneously 60 and automatically one clamp may be oper-

ated by the other, there is provided a link 27 axially aligned and connected to said clamps in such a manner and the relative connecting point between the clamps and the rock-shafts 23 is such that when one is 70 operated the pressure exerted upon said link 27 will be transmitted to the other clamp so as to impart to the same a similar motion. Thus, when one clamp is thrown from the clamping position to the ineffective position, 75 the other will simultaneously operate in the same manner and vice versa. To accomplish this, the link 27 is connected in the left-hand clamp 22 at 28 in thumb-lever 24 while in the right-hand clamp the link 27 is connected instead of a rearwardly-extending arm by means of screw 29. The springs 26 are mounted at one end by means of stationary spring-studs 30 on the table 21, and at the other end by means of similar 80 studs 31 fast upon the paper-clamps 22. When the clamps are swung from one position to the other, they will have to first overcome the tension of the springs 26 up to the point where they will pass the neutral 85 position in which the two studs 30 and 31 and the rock-shafts 23 are in line, but will be thrown the rest of their travel by the tension of the springs pulling in the other 90 direction, and, furthermore, will either hold 95 the clamps in their ineffective position or will hold them under tension against the table to support the narrow work-sheet.

The work-sheet-spacing guides are adjustably mounted upon the paper-table 20 and 100 comprise a pair of narrow sheet-guides 32 and a pair of wide sheet-guides 33.

When the work-sheets are placed in co-operative position with the platen and the sheet-guides, the lines along which typewriting is to be done may be at different heights upon the sheets and it will then be necessary to effect a relative adjustment of the sheets. To this end, the clamps 22 are provided so that the narrow or statement sheet 34 may 110 be held, while the wider or ledger sheet 35 may be positioned in relation to the former by means of the platen 10 and the pressure-rolls 18.

It will be noted that while inserting the 115 work-sheets, which include the customary carbon-paper between them, and the platen 10 is rotated to feed the sheets, the wide sheet 35 will get under paper-fingers 17 and being guided by the pressure-rolls 18 will 120 be fed between the table 21 and the platen 10, but the narrow sheet 34, due to the fact that it is not wide enough to enter the paper-fingers 17, will follow the path of least resistance, as shown by line 34a in Figure 3, and 125 will feed thus until it is forced to lie on table 21 to be held by paper-clamps 22. The table 21 is under cut in the center to assist in guiding the wider work-sheet under it, so 130 that it will first enter the ends and gradually

force the edges of the paper under the table.

Since the ledger-sheet 35 has to be collated relatively to the statement-sheet 34 which is in front of the ledger-sheet, it is necessary 5 to mark the ledger-sheet at one of its margins so as to identify the position of the last line of typing. Such a mark may be typed upon the sheet previously to withdrawing the same from the machine, and is 10 shown in Figure 1 indicated by the numeral 36.

Variations may be resorted to within the scope of the invention, and portions of the 15 improvements may be used without others.

Having thus described my invention, I claim:

1. The combination, in a typewriting machine, of means for simultaneously clamping both edges of a work-sheet upon a table at 20 the delivery side of the platen, said means including a pair of clamps pivotally mounted upon the table, a link pivotally connected to both clamps for a joint clamping movement, and springs operative to maintain each 25 clamp in clamping engagement with the work-sheet.

2. The combination, in a typewriting machine, of a revoluble platen, releasable feed-rollers co-operating therewith to feed a plurality of sheets therearound, inner and outer 30 adjustable side gages at the introductory side of the platen for collating wide and narrow superposed work-sheets, a table at the delivery side of the platen to support the narrow 35 work-sheet, means for simultaneously clamping both side edges of the narrow work-sheet against the table, and feeding means operative to engage the side margins of the wide inner sheet to collate the latter under the 40 clamped narrow sheet.

3. In a typewriting machine, in combination, a platen-frame including a platen and feed-rolls to co-operatively receive a plurality of superposed work-sheets, a table 45 mounted upon said platen-frame and carrying upon it two manually-operable paper-clamps co-operating with said table for effectively retaining the outer work-sheet, an over-center-spring arrangement for operatively controlling the extreme positions of 50 said paper-clamps and for positively holding said clamps in either effective or ineffective position, a link connecting said paper-clamps so that either one of the two 55 clamps may be operated by operating the other, and to simultaneously operate both from effective to ineffective position or vice versa, and means to hold the clamps in either effective or ineffective position, and 60 to positively force the clamps against the table to positively retain the outer work-sheet.

4. The combination, in a typewriting machine, of a revoluble platen, side gages at 65 the introductory side of the platen for col-

lating wide and narrow superposed work-sheets, releasable rollers running on the platen for feeding all the sheets therearound, means for temporarily clamping the narrow outer sheet after the positioning thereof, to permit collating of the wide inner sheet, said means including a table at the delivery side of the platen, a pair of clamps pivoted on both sides of said table for holding opposite edges of the outer sheet against 70 the table, and a link pivotally joining both clamps for a unitary movement thereof, and feeding means operative to engage the side margins of the wide inner sheet to collate the latter under the clamped narrow sheet. 75

5. The combination, in a typewriting machine, of means for simultaneously clamping both edges of a work-sheet upon a table adjacent the platen, at the delivery side thereof, said means including a pair of 80 clamps pivotally mounted upon said table, and a link pivotally connecting both clamps to promote a joint movement of the clamps.

6. The combination, in a typewriting machine, of means for simultaneously clamping both edges of a work-sheet upon a table adjacent the platen, at the delivery side thereof, said means including a pair of 85 clamps pivotally mounted upon said table, and pivotally connected to a link operative 90 to effect a joint vibration of the clamps in opposite directions.

7. The combination, in a typewriting machine, of means for clamping both edges of a work-sheet upon a table adjacent the 100 platen, at the delivery side thereof, said means including clamping members pivotally mounted upon said table, finger-pieces for operating the clamps, and means operatively connecting the finger-pieces to promote a joint operation of the clamps to operative or inoperative position. 105

8. The combination, in a typewriting machine, of means for clamping both edges of a work-sheet upon a table adjacent the 110 platen, at the delivery side thereof, said means including clamping members pivotally mounted upon said table, over-center springs arranged to hold the clamps in either effective or ineffective positions, 115 finger-pieces for operating said clamps, and means for operatively connecting the clamps to afford their simultaneous operation, said last-mentioned means including a rear extension on one of the clamps, a link operatively connected to said extension, and means for operatively connecting said link to the other clamp. 120

9. In a typewriting machine, the combination of a revoluble platen, two pairs of side 125 gages at the introductory side of the platen, one pair of the gages within the other pair for collating a wide and a narrow superposed work-sheet around the platen, rollers to feed both sheets around the platen, 130

means to temporarily clamp one sheet to permit the collating of the other sheet, said clamping means including a table at the delivery side of the platen and a pair of clamps arranged at opposite sides of said table to hold the opposite edges of one work-sheet against the table, and means for connecting the clamps together for a unitary clamping movement.

10 10. In a typewriting machine, the combination of a revoluble platen, two pairs of side gages at the introductory side of the platen, one pair of the gages within the other pair for collating a wide and a narrow super-

15 posed work-sheet around the platen, rollers

to feed both sheets around the platen, means to temporarily clamp one sheet to permit the collating of the other sheet, said clamping means including a table at the delivery side of the platen, and a pair of clamps arranged at opposite sides of said table to hold the opposite edges of one work-sheet against the table, means for connecting the clamps together for a unitary clamping movement, and feeding means operative at the exposed side edges of one sheet to collate said sheet under the other sheet while the latter is clamped to the table.

JESSE A. B. SMITH.
